(57) **CLAIM**

The ornamental design for a watch case, as shown and described.

DESCRIPTION

1.1 is a front view of a first embodiment of a watch case;
1.2 is a rear view thereof;
1.3 is a bottom view thereof;
1.4 is a top view thereof;
1.5 is a right view thereof;
1.6 is a left view thereof;
1.7 is a front perspective thereof;
2.1 is a front view of a second embodiment of the watch case;
2.2 is a rear view thereof;
2.3 is a bottom view thereof;
2.4 is a top view thereof;
2.5 is a right view thereof;
2.6 is a left view thereof; and
2.7 is a front perspective thereof.

The portions in the drawings shown in broken lines form no part of the claimed design.
